UNITED STATES PATENT OFFICE.

FRANK DITCHFIELD, OF CHICAGO, ILLINOIS, ASSIGNOR TO CAMEL COMPANY, OF CHICAGO, ILLINOIS, A CORPORATION OF ILLINOIS.

MOUNTING FOR SLIDING DOORS.

Application filed June 15, 1925. Serial No. 37,061.

The present invention relates to mountings for sliding doors.

The present invention will be described in connection with the sliding doors of railway freight cars. Such sliding doors have in the past been provided with rollers, but special construction has been required for maintaining the rollers in their proper positions relative to one another and relative to the parts with which they have rolling engagement.

An object of the present invention is to provide a mounting for a sliding door which is inexpensive to manufacture and assemble and simple in operation.

A further object is to provide roller bearings for a sliding door which roller bearings, though simple in structure, will be effective in service.

A further object is to provide roller bearings for sliding doors which will have the advantage that the rollers will always be disposed in proper position.

Further objects will appear as the description proceeds.

Referring to the drawings—

Figure 1 is a fragmentary view illustrating part of the side of a railway box car;

Figure 2 is a fragmentary sectional view of the railway box car shown in Figure 1, said view being taken along the plane indicated by the arrows 2—2 of Figure 1;

Figure 3 is a view, on an enlarged scale, of part of the structure shown in Figure 1; and

Figure 4 is a fragmentary view in section showing a modified arrangement.

The numeral 1 indicates the side wall of a railway box car. Said side wall is provided with a door opening adapted to be closed by the sliding door 2. Said sliding door is shown in full lines in closed position, the open position of said sliding door being indicated in broken lines. The side plate of the wall 1 of the box car is provided with the angle 3, to which is secured the guard 4. Said angle 3 provides a track extending longitudinally of the car wall for a sufficient distance to support the sliding door 2 throughout its range of sliding movement. Said sliding door 2 is provided at its top with the Z-bar 5 having the flange 6 lying between the guard 4 and the side plate of the car. Movement of the door 2 in a direction transversely of the car is therefore limited by the side plate of the car and said

guard 4, whereby said door 2 is guided in its longitudinal movement.

Secured on the outer side of the door 2 adjacent to the upper edge of said door are a pair of brackets 7—7. Said brackets 7—7 have riveted thereto the angle 8, which, as shown in Figure 1, lies in parallel relationship with the door 2 and extends a short distance beyond each of the two side edges of said door 2. Said angle 8 and the track 3 provide bearing members for a pair of rollers 9—9, whereby the door 2 may be moved with a sliding motion with a minimum of effort. Each of the brackets 7—7 is provided with a pin 10 forming a support for a roller 11, which is adapted to abut against the under surface of the guard 4, whereby to limit upward movement of the door 2 and to minimize the danger of jamming.

According to the illustrated embodiment of the present invention two rollers 9—9 are provided. Said rollers should be disposed in spaced relationship with one another and should be spaced apart a sufficient distance so that binding and tipping of the door 2 will be avoided. According to the disclosure of Figure 1, said rollers 9—9 are so disposed that when the door is in closed position, one of the rollers 9 is adjacent to the rear end of the angle 8, and when the door is in full open position, the other roller 9 is adjacent to the forward end of said angle 8. As will be explained, the rollers 9—9 are geared to the angle 8 and to the angle 3, so that the range of movement of each roller 9 is one-half of the range of movement of the door 2. The geared connection referred to is provided by projecting studs and cooperating recesses.

Referring to Figures 2 and 3, the angle 8 is provided with a plurality of rivets 12—12 having substantially conical head portions 13—13, forming studs, projecting downwardly from the horizontal wall of the angle 8. The angle 3 is provided with a plurality of spaced rivets 14—14, which are provided with the conical heads 15—15, forming studs, projecting upwardly from the horizontal surface of the track 3. The rivets 12—12 and 14—14 are spaced equally along the angle 8 and the track 3, and the axes of the rivets 12 are in vertical alignment with the axes of rivets 14—14. Each of the rollers 9—9 is provided with spaced conical aper-

tures 16—16, the axes of said apertures being equally spaced with the conical heads 13—13 and 15—15. The height of the conical heads 13—13 and 15—15 should be greater than the range of lifting movement of the door 2 permitted by the rollers 11—11, so that there is no danger of the rollers 9—9 becoming misplaced from the rivet heads 13—13 and 15—15.

19 In the modified structure shown in Figure 4 the roller 16', instead of being provided with spaced holes as is the roller 9 shown in Figures 1, 2 and 3, is provided with spaced conical projections 17—17 adapted to seat 15 within spaced holes 18—18 in the structural steel members carried by the sliding door and the frame of the car.

The structure shown in Figure 4 is a bottom hung job. Carried by the side sill 19 20 of the car are a plurality of brackets 20, which support the angle 21. Carried at the lower extremity of the door 2 is the structural steel member 22 having the web 23 disposed underneath the lower edge of the door 25 and having the flange 24 extending downwardly from the web 23. The flange 24 cooperates with the angle 21 to guide the door 2 in its sliding movement.

It will be clear without detailed explanation that when the door 2 is moved with a sliding motion, said sliding motion will be accomplished on the roller bearings provided by the rollers 9—9 of Figures 1, 2 and 3, or by corresponding rollers 16' as shown in Figure 4. The cooperating conical parts of said rollers and their cooperating bearing members will be engaged during the sliding movement of the door 2, and said rollers will be maintained in predetermined spaced relationship with one another. Said rollers will travel half the distance to which the sliding door 2 is moved and will always be in operative position. The fact that said rollers will have a range of travel of only half the maximum distance through which the door 2 will be moved renders it possible to space said rollers apart a very considerable distance without necessitating an excessively long angle 8 to maintain said rollers in operative position throughout the range of movement of said door.

The present invention is simple and inex-

pensive, is easy to assemble, is positive in its action and will not get out of operative relationship in service.

Though a preferred embodiment of the present invention has been described in detail, it will be clear that many modifications will occur to those skilled in the art. It is intended to cover all such modifications that fall within the scope of the appended claims.

What is claimed is—

1. In combination, a car frame, a sliding door, a track carried by said car frame, an elongated metal member carried by said door, a pair of rollers between said track and said elongated metal members, said rollers being provided with recesses uniformly spaced about their peripheries, said track member and elongated metal member being 65 provided with projections adapted to mesh with said recesses, said track member having on its under side a structural steel member providing a downwardly extending flange for limiting outward movement of said door, 70 the projections upon said track member comprising rivets having the function of securing said structural steel member to said track member.

2. In combination, a car frame, a sliding 80 door, a track carried by said car frame, an elongated metal member carried by said door, a pair of rollers between said track and said elongated metal members, said rollers being provided with recesses uniformly 85 spaced about their peripheries, said track member and elongated metal member being provided with projections adapted to mesh with said recesses, said track member having on its under side a structural steel member 90 providing a downwardly extending flange positioned intermediate of the width of said track member, said door being provided with an upwardly projecting flange disposed inwardly of said downwardly projecting flange and having rollers for limiting upward movement of said door, said projections upon said track member including rivets having smooth heads on their under sides for securing said structural steel member to said track member.

Signed at Chicago, Illinois, this 1st day of June, 1925.

FRANK DITCHFIELD.
